UNITED STATES PATENT OFFICE.

ALBERT P. LEE, OF CHICAGO, ILLINOIS, ASSIGNOR TO LEE TRAILER & BODY COMPANY, OF CHICAGO, ILLINOIS.

RAIL CONSTRUCTION FOR ROLLING HOPPERS.

1,384,905.

Specification of Letters Patent.

Patented July 19, 1921.

Application filed July 28, 1920. Serial No. 399,520.

To all whom it may concern:

Be it known that I, ALBERT P. LEE, a citizen of the United States, residing at Chicago, in the county of Cook and State 5 of Illinois, have invented a certain new and useful Improvement in Rail Construction for Rolling Hoppers, of which the following is a full, clear, concise, and exact description, reference being had to the accompanying drawings, forming a part of this 10 specification.

This invention relates to rolling hoppers and more particularly to the construction of the rails upon which the hoppers are adapted 15 to roll.

In providing a dumping hopper for vehicles in which the hopper is adapted to roll automatically from a load carrying position to a dumping position and to complete the 20 dumping action by a pivotal movement about a point at or near the end of the rail, it has been found that some means must be provided to prevent the hopper from becoming disengaged at its pivots, 25 while the pivotal movement is going on. It is a purpose of this invention to provide a rail of the above character with means to effectively prevent the disengagement of the hopper from its pivots.

More particularly it is the purpose of this invention to provide a rail having portions extending downwardly from the center thereof, and provided with pivot means at the ends thereof, with means to prevent the 35 disengagement of the hopper from said pivot means while the hopper is pivoting thereon.

It is a further object of the invention to provide a vehicle carrying a hopper having pivot pins thereon, with rails upon which 40 said hopper may roll, having socket members at its ends in which said hopper may pivot on said pins that are provided with guards to prevent the pins from leaving the sockets while the hopper is in such position 45 that it is supported entirely by said pins and sockets, and thus prevent the hopper from tilting off the ends of the rails to the ground.

Other objects and advantages of the 50 invention will appear as the description of the accompanying drawings proceeds, in which like characters of reference are used to designate like parts, and in which

Figure 1 is an end view of a rolling hopper, showing one of the rails associated 55 therewith in side elevation, and

Fig. 2 is a top plan view of one of the rail ends.

Referring in detail to the drawings, the invention comprises the hopper 3 having 60 the bearing rail 4 thereon with a curved portion 5 adapted to coöperate with the rail 6 mounted on the vehicle framework 7 in any suitable manner. The hopper 3 is provided with pivot pins 8 where the curved 65 portions 5 of the bearing rail meet the straight portions thereof.

In Fig. 1 the hopper 3 is shown in its central load carrying position and this hopper is held in this position by suitable retaining devices (not shown), and when these are released it is adapted to roll automatically from the central portion 9 of the rail 6 in either direction down the inclined portions 10 thereof and the curved bearing rail 75 portion 5 of the hopper and the inclined portions 10 of the rail 6 are so proportioned that when the hopper has rolled to the end of the curved portion of the bearing rail pins 8 will engage in their respective hook-shaped members 11 which are secured to the 80 end portions of the rail 6 and the hopper will pivot on said pins 8 in the sockets 12 formed in the hooked brackets 11 and complete the dumping operation of the hopper. 85

As shown in Fig. 2, the brackets 11 are bifurcated and have a portion 13 extending on each side of the web portion of the rail 6, the rail being in the form of an I-beam and these bifurcated portions 13 are secured 90 to the web in any suitable manner as by rivets 14. It will be seen on referring to Fig. 1 that the bracket 11 is rigidly secured to the rail 6 by means of the rivets 14 as the edge portions of the bifurcated portions 95 13 engage the flanges of the I-beam both at the top and bottom thereof thus forming a very strong and rigid structure.

It has been found that when the hopper 3 is in the position shown in Fig. 1 in dotted 100 lines or while the same is pivoting on the pin 8 there is a tendency for the pin 8 to travel upwardly relatively to the socket 12 and to become disengaged therefrom and thus cause the hopper to fall off the rails 105 onto the roadway. In order to avoid this

the upper webs 15 of the rails 6 have been extended as shown at 16 to partially close the mouth of the socket 12 but leaving sufficient space for the pin to roll off the end of the portion 16 and into the socket 12. As the tendency of the pin 8 is to travel upwardly and rearwardly as the hopper pivots to its final dumping position the pin will move from the bottom of the socket toward 10 the member 16 and between the member 16 and the rear wall of the socket referred to by the numeral 17 in Fig. 1, thus preventing the disengagement of the pin and socket while the pivotal movement is going on or 15 after the hopper has reached its final dumping position.

Upon referring to Figs. 1 and 2 it will be seen that the hook-shaped bracket 11 can be reinforced in any suitable manner as by the web 18. From the foregoing description it will be seen that a rail for rolling hoppers is provided that has socket members mounted on the ends thereof about which the hopper may pivot and which socket members 25 are provided with guards to prevent the disengagement of the pivot pins carried by the hopper from the sockets.

Having thus described my invention I desire to have it understood that I do not 30 intend to limit myself to the exact details of construction shown in the accompanying drawings or described in the foregoing

specification except as defined by the following claims:

1. In a device of the character described, 35 the combination of a rail, a hopper adapted to roll on said rail from charge carrying to discharge position, coöperating pivot members on said rail and hopper comprising a pin and a socket portion in which said pin 40 is adapted to pivot, and an overhanging guard to hold said pin in said socket when said hopper reaches its limiting dumping position.

2. In a device of the character described, 45 a rail having a socket member secured to the end portion thereof, and an extension on said rail extending partially over the mouth of said socket to act as a guard for the same.

3. In a device of the character described, a rail having a socket member secured to the end portion thereof, means adapted to enter said socket and pivot therein, and a finger extending partially over the mouth 55 of said socket to provide a constricted entrance opening to said socket, said opening being positioned out of the normal path of movement of said means in said socket member as the pivoting movement is completed. 60

In witness whereof, I hereunto subscribe my name this 16th day of July, A. D. 1920.

ALBERT P. LEE.
